(57) **CLAIM**

The ornamental design for a cosmetic applicator container, as shown and described.

DESCRIPTION

FIG. 1 is an elevated side view of a cosmetic applicator container according to a first embodiment of the present invention;

FIG. 2 is a front view of a cosmetic applicator container according to a first embodiment of the present invention;

FIG. 3 is a back view of a cosmetic applicator container according to a first embodiment of the present invention;

FIG. 4 is a right side view of a cosmetic applicator container according to a first embodiment of the present invention;

FIG. 5 is a left side view of a cosmetic applicator container according to a first embodiment of the present invention;

FIG. 6 is a top view of a cosmetic applicator container according to a first embodiment of the present invention;

FIG. 7 is a bottom view of a cosmetic applicator container according to a first embodiment of the present invention;

FIG. 8 is an elevated side view of a cosmetic applicator container according to a second embodiment of the present invention;

FIG. 9 is a front view of a cosmetic applicator container according to a second embodiment of the present invention;

FIG. 10 is a back view of a cosmetic applicator container according to a second embodiment of the present invention;

FIG. 11 is a right side view of a cosmetic applicator container according to a second embodiment of the present invention;

FIG. 12 is a left side view of a cosmetic applicator container according to a second embodiment of the present invention;

FIG. 13 is a top view of a cosmetic applicator container according to a second embodiment of the present invention;

FIG. 14 is a bottom view of a cosmetic applicator container according to a second embodiment of the present invention;

FIG. 15 is an elevated side view of a cosmetic applicator container according to a third embodiment of the present invention;

(Continued)

FIG. 16 is a front view of a cosmetic applicator container according to a third embodiment of the present invention; FIG. 17 is a back view of a cosmetic applicator container according to a third embodiment of the present invention; FIG. 18 is a right side view of a cosmetic applicator container according to a third embodiment of the present invention;

FIG. 19 is a left side view of a cosmetic applicator container according to a third embodiment of the present invention; FIG. 20 is a top view of a cosmetic applicator container according to a third embodiment of the present invention; FIG. 21 is a bottom view of a cosmetic applicator container according to a third embodiment of the present invention; FIG. 22 is an exploded elevated side view of a cosmetic applicator container showing possible internal components according to a fourth embodiment of the present invention; FIG. 23 is an exploded front view of a cosmetic applicator container showing possible internal components according to a fourth embodiment of the present invention; FIG. 24 is an exploded back view of a cosmetic applicator container showing possible internal components according to a fourth of the present invention;

FIG. 25 is an exploded right side view of a cosmetic applicator container showing possible internal components according to a fourth embodiment of the present invention; FIG. 26 is an exploded left side view of a cosmetic applicator container showing possible internal components according to a fourth embodiment of the present invention; FIG. 27 is an exploded top view of a cosmetic applicator container showing possible internal components according to a fourth embodiment of the present invention;

FIG. 28 is an exploded bottom view of a cosmetic applicator container showing possible internal components according to a fourth embodiment of the present invention; and, FIG. 29 is a front view of a packaging arrangement for cosmetic applicator containers according to an embodiment of the invention.

The broken line showing of the cosmetic applicator container is for the purpose of illustrating environmental structure and forms no part of the claimed design.
